[57] ABSTRACT

A plurality of memories are provided for storing, in analog representation, the sampled values of a one cycle sinusoidal wave of the fundamental frequency, a two cycle sinusoidal wave of the second harmonic, . . . and an m cycle sinusoidal wave of the m -th harmonic. These memories are read at the same reading rate. The read out sinusoidal wave are controlled in their relative levels in accordance with the tone-color and amplitude of a musical tone wave shape to be obtained. The sinusoidal waves thereafter are synthesized to produce the desire tone-color wave shape. The levels of the read out sinusoidal waves are controlled by changing the amplification degree of variable amplifiers respectively provided on the output side of the respective memories.

Alternatively, memories are provided for storing these sinusoidal waves digitally. The digital signals read from these memories are applied to corresponding multipliers. The multipliers receive, on the other hand, digital control signals for controlling the level of each sinusoidal wave in accordance with the tone-color and amplitude of the musical tone wave shape to be obtained. These two kinds of digital signals are multiplied with each other in these multipliers. The outputs of the multipliers are applied to an adder, where they are added together. A digital signal representing the addition result is converted to an analog signal by a digital-to-analog converter to produce the desired musical tone wave shape.

FIG. 4

MUSICAL TONE WAVE SHAPE GENERATING APPARATUS

This invention relates to a musical tone wave shape generating apparatus and, more particularly, to a musical tone wave shape generating apparatus capable of producing a musical tone wave shape of a desired tone-color by synthesizing a fundamental wave and a plurality of harmonics which are in harmonic relation with the fundamental frequency at appropriate ratio according to the desired tone-color.

A musical tone wave shape can be divided into a fundamental wave component and one or more harmonic components, no matter how complicated the wave shape may appear. Conversely, a desired musical tone wave shape can be obtained by synthesizing its fundamental wave and one or more predetermined harmonics at appropriate ratios of levels. The present invention makes use of this principle.

A specific musical tone wave shape may be obtained by providing a memory which stores this specific musical tone wave shape and reading it from the memory. It is very difficult, however, to change the contents once stored in the memory. In order to obtain a plurality of different musical tone wave shapes, it is therefore necessary to provide a plurality of memories which respectively store one of the different wave shapes. If the number of required musical tone wave shapes is large, a corresponding large number of memories are required. Furthermore, a desired musical tone wave shape will not always be obtained from one of these memories if the desired wave shape is not stored in any of the memories.

It is, therefore, an object of this invention to provide an apparatus capable of producing any desired musical tone wave shape by using only a small number of memories.

It is another object of the invention to provide an apparatus capable of producing a desired musical tone wave shape by providing a plurality of memories which respectively store, in sampled analog representation, the fundamental frequency of the musical tone wave shape and a plurality of its harmonics and reading these waves simultaneously from these memories and synthesizing the read out outputs at a suitable relative level ratio.

It is another object of the invention to provide an apparatus capable of producing a desired musical tone wave shape by providing a plurality of memories which respectively store, in digital representation, the fundamental wave and a plurality of its harmonics, reading information corresponding to these waves simultaneously from these memories, multiplying digitally the relative levels of the read out outputs with each other, thereafter adding digitally the read out outputs together and converting the digital signal to an analog signal to produce the desired musical tone wave shape.

It is another object of the invention to provide an apparatus in which the relative levels of the outputs read from a plurality of memories respectively storing digitally the fundamental wave and its harmonics are controlled in accordance with the outputs of spectra memories which store digitally predetermined relative levels of these outputs.

These and other objects and features of the invention will become apparent from the description made here-

inbelow with reference to the accompanying drawings in which:

FIG. 1 is a block diagram showing one embodiment of the musical tone wave shape generating apparatus according to the invention;

FIG. 2 is a circuit diagram showing one example of the wave shape memory shown in FIG. 1;

FIG. 3 is a block diagram showing another embodiment of our musical tone wave shape generating apparatus incorporating memories which store wave shapes in digital representation;

FIG. 4 is a block diagram showing another embodiment of our musical tone wave shape generating apparatus incorporating memories which, like the ones shown in FIG. 3, store wave shapes in digital representation and further incorporating spectra memories which store digitally predetermined relative levels of the fundamental wave component and each harmonic component of a desired musical tone wave shape.

Referring first to FIG. 1, a clock pulse generator 1 provides, according to the note to be played, pulses of Nf Hz to a counter 2 of n (e.g. 6) stages (where $N = 2^2$ and f represents the fundamental frequency of the musical tone wave shape to be obtained). Wave shape memories M_1 through M_m respectively store sinusoidal waves. The memory M_1 stores the fundamental wave, M_2 the second harmonic . . . , M_m the m -th harmonic. In the preparation of each memory, each wave shape to be stored is sampled by a suitable sampling number N (e.g. 64) and the wave shape amplitudes at respective sample points are stored in analog values. The fundamental wave memory M_1 stores amplitudes of one cycle of a sinusoidal wave, the second harmonic memory M_2 stores amplitudes of two cycles of a sinusoidal wave and each subsequent memory stores in the same manner amplitudes of cycles of a sinusoidal wave to be stored. The bit output of each stage of the counter 2 is provided to decoders D_1 through D_m simultaneously.

Each of the decoders D_1 through D_m provides, upon receipt of each bit output of the counter 2, its output on one of its individual output lines L_1 through L_n one after another according to the state of the bit output, just as the outputs from a ring counter. Accordingly, when a pulse is applied from the clock pulse generator 1 to the counter 2 in a reset state, the decoders D_1 through D_m produce outputs on the output lines L_1 . When a next pulse is applied to the counter 2, the decoders D_1 through D_m produce outputs on the output lines L_2 . Thereafter the decoders D_1 through D_m produce outputs on the output lines L_3 , L_4 . . . , one line after another, each time a clock pulse is applied to the counter 2. After the output line L_n , the output is again produced on the output line L_1 and this process is repeated cyclically.

FIG. 2 shows one example of construction of the memories M_1 through M_m . A sinusoidal wave to be stored is sampled by the sampling number N and the amplitude at each sample point is stored by means of resistor values according to a predetermined voltage dividing ratio. Reference character A_1 designates a connection point of resistors R_{1a} and R_{1b} , A_2 a connection point of resistors R_{2a} and R_{2b} , . . . and A_n a connection point of resistors R_{na} and R_{nb} respectively. Since a constant voltage is applied between a terminal T_{1n} and ground, voltages at these connection points A_1 through A_n are $R_{1b}V/R_{1a} + R_{1b}$, $R_{2b}V/R_{2a} + R_{2b}$, . . . $R_{nb}V/R_{na} + R_{nb}$ respectively. These voltages respectively corre-

spond to the values of amplitudes of the wave shape to be stored. The drains of transistors T_1 through T_n are respectively connected to the corresponding connection points A_1 through A_n . The source of each of the transistors T_1 through T_n is connected to the sources of its adjacent transistors in common and also to an output terminal T_{out} . The gates of these transistors T_1 through T_n are respectively connected to the output lines L_1 through L_n .

Accordingly, when the decoder D produces outputs successively on the output lines $L_1, L_2, \dots, L_n$, the transistors T_1 through T_n conduct in time sequence and provide the above described predetermined voltages to the output terminal T_{out} . Thus the sinusoidal wave shape stored in the memory M is read out.

Referring again to FIG. 1, variable amplifiers VA_1 through VA_m are respectively connected to the output terminals of the memories M_1 through M_m to control the levels of the wave shape outputs of the memories M_1 through M_m . The wave shape outputs thus controlled in their level by the variable amplifiers VA_1 through VA_m are thereafter synthesized and taken out of an output terminal 3.

The amplification factors of the variable amplifiers VA_1 through VA_m are variable in accordance with the values of voltages applied thereto (hereinafter called "control signals"). These control signals are produced in gain control circuits C_1 through C_m , which will be described more in detail hereinbelow.

Tone-color selection and control knobs S_a through S_h are provided corresponding to tone-colors A through H to be obtained. The sliders of variable resistors VR_a through VR_h are operable by manipulation of these knobs S_a through S_h . A constant voltage V is applied to one end of each of these variable resistors VR_a through VR_h . The slider of the variable resistor VR_a is connected to the input terminals of the gain control circuits C_1 through C_m via resistors $R_{a1}, R_{a2}, \dots, R_{am}$. Similarly, the slider of the variable resistor VR_b is connected to the input terminal of the gain control circuits C_1 through C_m via resistors $R_{b1}, R_{b2}, \dots, R_{bm}$. The sliders of the other variable resistors are likewise connected to the input terminals of the gain control circuits C_1 through C_m .

The resistors R_{a1} through R_{am} are provided to determine the ratio of levels of the fundamental wave, the second harmonic, . . . and the m -th harmonic whereas the variable resistor VR_a is provided to obtain the tone-color wave shape thus constituted at a desired level or amplitude. The foregoing description is also applicable to the other resistors R_{b1} through R_{bm} , . . . R_{h1} through R_{hm} and the variable resistors VR_b through VR_h .

For convenience of explanation, let it be assumed that the knobs S_b through S_h and a knob S_x to be described later are set at a 0 amplitude position and the knob S_a is set at a suitable position other than 0 amplitude. The gain control circuit C_1 receives a voltage which is determined by the resistor R_{a1} and the position of the slider of the variable resistor VR_a . This d-c voltage is amplified in the gain control circuit C_1 and thereafter is applied to the control terminal of the variable amplifier VA_1 as the control signal. Accordingly, the amplification factor of the variable amplifier VA_1 becomes one which corresponds to the control signal and the fundamental wave output of the memory M_1 is taken out of the output terminal of the variable amplifier VA_1 at a level which corresponds to this amplifica-

tion factor. The gain control circuit C_2 likewise receives a voltage which is determined by the resistor R_{a2} and the position of the slider of the variable resistor VR_a and controls the level of the second harmonic output. The same is the case with the other harmonic outputs.

Thus, a predetermined musical tone wave shape at a predetermined level is produced by setting the tone-color selection and control knob S_a at a suitable position. Other predetermined musical tone wave shapes at predetermined levels are also produced by manipulating the knobs $S_b \dots S_h$.

If several knobs are selected and set at suitable positions, a composite voltage of the set levels of the tone-colors corresponding to these selected knobs is provided at the output terminal of each of the control circuits C_1 through C_m as the control signal for each of the fundamental wave, the second harmonic . . . the m -th harmonic. Consequently, a musical tone wave shape which is composed of said plurality of tone-colors is provided at the output terminal 3 at a desired level.

FIG. 3 shows another embodiment of the musical tone wave shape generating apparatus according to the invention. The main difference between the present embodiment and the above described embodiment is that wave shape memories Ma_1 through Ma_m used in the present embodiment store the wave shape amplitudes digitally and that the wave shapes which are simultaneously read from these memories are digitally controlled in their levels and synthesized and thereafter are converted to analog signals to produce the desired musical tone wave shape. Hence the same component parts in FIGS. 1 and 3 are designated by the same reference characters and a detailed explanation of these component parts will be omitted in the description to follow.

Each of the wave shape memories Ma_1 through Ma_m consists, for example, of a read only memory (ROM) which stores amplitudes at respective sample points of the sampled sinusoidal wave in the form of binary information consisting of multiple bits. The memory Ma_1 stores the fundamental wave, Ma_2 the second harmonic . . . and Ma_m the m -th harmonic respectively. The fundamental wave memory Ma_1 stores amplitudes of one cycle of a sinusoidal wave, the second harmonic memory Ma_2 stores amplitudes of two cycles of a sinusoidal wave and each subsequent memory stores in the same manner amplitudes of m cycles of a sinusoidal wave. Each wave shape to be stored in these memories is sampled by a sampling number N (e.g. 64).

As the outputs of decoders D_1 through D_m are successively applied to the memories Ma_1 through Ma_m , digital signals representing the stored amplitudes are successively read from these wave shape memories Ma_1 through Ma_m . These digital signals consist, for example, of eight bits. Multipliers ML_1 through ML_m are respectively connected to the memories Ma_1 through Ma_m . The multipliers ML_1 through ML_m multiply the digital signals thus read from the memories Ma_1 through Ma_m with control signals to be described later, thereby controlling the levels of the outputs of the memories Ma_1 through Ma_m in response to the control signals. The controlled outputs are taken out as digital signals consisting, for example, of eight bits. The control signals are also digital signals consisting, for example, of five bits.

Assume now, for convenience of explanation, that tone-color selection and control knobs S_b through S_h and S_x are set at a **0** amplitude position and a tone-color selection and control knob S_a is set at a suitable position other than the **0** amplitude position. A voltage determined by a resistor R_{a_1} and the position of the slider of a variable resistor VR_a is applied to the input terminal of an analog-to-digital converter A_1 . This voltage is converted by the analog-to-digital converter A_1 to a binary signal of a suitable number of bits, e.g. 5 and applied to the multiplier ML_1 as a control signal. Accordingly, the digital signal from the memory M_1 is multiplied with this control signal in the multiplier ML_1 , and the result (mathematical product) of the multiplication is provided as the output of the multiplier ML_1 . This output contains, for example, eight digits counting from the most significant digit, the remaining digits being discarded. The contents of the eight bit digital signal produced at the output terminal of the multiplier ML_1 represent a wave shape amplitude of the fundamental wave controlled in its level by the above described control signal. In other words, the fundamental wave output controlled in its level is provided in the form of a digital signal at the output of the multiplier ML_1 . Similarly, a voltage determined by a resistor R_{a_2} and the position of the slider of a variable resistor VR_b is applied to an analog-to-digital converter A_2 . The analog-to-digital converter A_2 converts this voltage to a digital signal and applies it to the multiplier ML_2 as a control signal, thereby causing the multiplier ML_2 to produce the second harmonic output controlled in its level in the form of a digital signal. The same principle of operation applies to the other harmonic outputs from the multipliers ML_3 through ML_m .

Digital signals produced in the multipliers ML_1 through ML_m are applied to an adder ADD where these signals are added together. The result of the addition is provided as the output of the adder ADD in the form of a digital signal containing, for example, twelve digits counting from the most significant (i.e., highest order) digit. This digital signal is applied to a digital-to-analog converter DA where it is converted to an analog signal and taken out of an output terminal **3**. It will be understood from the foregoing description that this output is a synthesized musical tone wave shape composed of the sinusoidal wave outputs from the memories M_{a_1} through M_{a_m} which are controlled in their levels by the control signals from the analog-to-digital converters A_1 through A_m .

Thus, a predetermined musical tone wave shape at a predetermined level is obtained by setting the tone-color selection and control knob S_a at a suitable position. Other predetermined musical tone wave shapes at desired levels are also obtainable by manipulating the other knobs S_b through S_h .

If several knobs are set at suitable positions, a composite voltage of the levels of the selected tone-colors is applied to each of the analog-to-digital converters A_1 through A_m for controlling the fundamental wave and each harmonic. Accordingly, a musical tone wave shape composed of said plurality of tone-colors is provided at the output terminal **3**.

In the foregoing two embodiments, the resistors R_{a_1} through R_{a_m} , R_{b_1} through R_{b_m} , . . . R_{h_1} through R_{h_m} respectively have predetermined values of resistance for determining the relative levels of the fundamental wave and each harmonic, and predetermined musical

tone wave shapes are obtained by manipulating the knobs S_a through S_h . For obtaining a special tone-color other than these predetermined tone-colors, variable resistors R_{x_1} through R_{x_m} may be inserted in addition to the fixed resistors between the knob S_x and the gain control circuits C_1 through C_m in the case of the embodiment shown in FIG. 1, and between the knob S_x and the analog-to-digital converters A_1 through A_m in the case of the embodiment shown in FIG. 3. The resistance of these variable resistors R_{x_1} through R_{x_m} can be individually adjusted to suitable values. Reference characters VR_x designate a variable resistor which can be operated by the knob S_x .

In the embodiments described above, the variable resistors VR_a through VR_x may be replaced by tapped resistors and change over switches. In this case, a synthesized musical tone wave shape determined by the relative state of these switches is provided at the output terminal **3**, although the apparatus is incapable of variably controlling the amplitude of each tone-color continuously.

FIG. 4 shows another embodiment of the apparatus according to the invention. This embodiment is different from the embodiment shown in FIG. 3 in the circuit arrangement for producing control signals applied to the multipliers ML_1 through ML_m . In FIGS. 3 and 4, the same component parts are designated by the same reference characters and a detailed explanation of these component parts will be omitted in the description to follow.

In FIG. 4, switch knobs S_1 through S_{20} are provided as tone-color selection knobs. The tone-color selection knobs S_1 through S_{20} respectively correspond to tone-colors to be obtained and are adapted to operate the sliders of variable resistors VR_1 through VR_{20} . A constant voltage is applied to one end of each of the variable resistors VR_1 through VR_{20} . The sliders of the variable resistors VR_1 through VR_{20} are respectively connected to analog-to-digital converters A_{a_1} through $A_{a_{20}}$. The voltage applied to the analog-to-digital converters A_{a_1} through $A_{a_{20}}$ is converted to digital signals X_1 through X_{20} consisting, for example, of four bits. These digital signals X_1 through X_{20} are applied to the input terminals on one side of multipliers MM_1 through MM_{20} . These signals X_1 through X_{20} respectively represent each tone-color and its amplitude.

Each of spectra memories SM_1 through SM_{20} consist, for example, of a read only memory (ROM) and stores digitally a signal for determining the relative levels of the fundamental wave and each harmonic of the desired musical tone wave shape.

Assume, for convenience of explanation, that the knob S_1 is set at a suitable position other than a **0** amplitude position, that the analog-to-digital converter A_{a_1} produces the output X_1 and that the remaining knobs S_2 through S_{20} are all set at the **0** amplitude position. The spectra memory SM_1 provides a digital signal K_1 consisting, for example, of five bits and determining the level of the fundamental wave, a digital signal K_2 determining the level of the second harmonic . . . and a digital signal K_m determining the level of the m -th harmonic to the input terminals on the other side of the multiplier MM_1 . These signals K_1 through K_m are multiplied with the signal X_1 in the multiplier MM_1 . As a result, the multiplier MM_1 produces digital signals $K_1 \cdot X_1$, $K_2 \cdot X_1$, . . . , $K_m \cdot X_1$ at the output terminals thereof.

The signal K_1X_1 is applied to an adder ADD_1 , the signal K_2X_1 to an adder ADD_2 , . . . the signal K_mX_1 to an adder ADD_m respectively. No other inputs are applied to these adders ADD_1 through ADD_m under the assumed condition. Accordingly, the output of the adder ADD_1 is K_1X_1 . This output K_1X_1 of the adder ADD_1 is applied to the other input terminal of the multiplier ML_1 as a control signal. The wave shape digital signal from the memory Ma_1 is multiplied with this control signal in the multiplier ML_1 . The result of the multiplication is provided as the output of the multiplier ML_1 . This output contains, for example, eight digits counting from the most significant digit, the remaining digits being discarded. The digital signal from the multiplier ML_1 represents the wave shape amplitude of the fundamental wave controlled in its level by the control signal. Thus, the fundamental wave output the level of which corresponds to that of the desired tone-color is obtained as a digital signal at the output terminal of the multiplier ML_1 .

Similarly, a control signal K_2X_1 is produced as the output of the adder ADD_2 and the second harmonic output corresponding in its level to the desired tone-color is produced from the multiplier ML_2 . The same operation principle applies to the other harmonic outputs.

The foregoing description has been made with regard to the case wherein the musical tone wave shape of the tone-color corresponding to the knob S_1 only is to be obtained. For obtaining a musical tone wave shape composed of a plurality of tone-colors by manipulating a plurality of knobs, digital signals are applied from predetermined ones among the multipliers MM_1 through MM_{20} to the adders ADD_1 through ADD_m . The adders ADD_1 through ADD_m respectively add the digital signals of five bits and supply sum signals each containing, for example, eight digits counting from the most significant digit to the multipliers ML_1 through ML_m as control signals of eight bits. Other operations are the same as described hereinabove with respect to the case wherein only the knob S_1 is operated.

The digital signal outputs from the multipliers ML_1 through ML_m are applied to the adder ADD where these signals are added together. The result of the addition including, for example, 12 digits counting from the most significant digit is applied to the digital-to-analog converter DA . Thus, the desired musical tone wave shape composed of the fundamental wave and each harmonic having predetermined relative levels is provided at the output terminal 3.

The spectra memories SM_1 through SM_{20} store specific wave shapes according to a tone-color to be obtained. If it is desired to change the tone-color, these spectra memories may be detachably connected to the multipliers so that they may be replaced by other ones corresponding to the new tone-colors.

The portion Q enclosed by a dotted line in FIG. 4 shows another feature of the apparatus according to this invention. A spectra memory SM_x consists of a memory such as a random access memory (RAM) in which information can be written. In order to change the information stored in this memory SM_x , a punched card PC containing information corresponding to the levels of the fundamental wave and each harmonic is inserted into a reading device $R0$ and the output of the reading device $R0$ is applied to the memory SM_x . The output of a variable resistor VR_x is converted to a digi-

tal signal in an analog-to-digital converter Aax and applied to a multiplier MM_x . The output of the multiplier MM_x is applied to the adders ADD_1 through ADD_m and the same operation as described hereinabove is performed to produce the desired musical tone wave shape at the output terminal 3.

In the foregoing embodiments, the frequency of the clock pulse from the clock pulse generator 1 was represented as Nf and the musical tone wave shape having the fundamental frequency f , i.e., the wave shape of a musical tone at a specific pitch corresponding to the frequency f is obtained at the output terminal 3. According to the invention, each memory is read at the same reading rate so that the wave shape of a musical tone at a desired pitch can be obtained by merely varying the frequency of the clock pulse from the clock pulse generator 1.

What we claim is:

1. Apparatus for synthesizing electrical wave shapes for conversion into musical tones, comprising
  - a. a plurality of memories for storing in analog representation respective consecutive series of amplitudes of a fundamental sinusoidal wave and of selected harmonics thereof;
  - b. a corresponding plurality of read-out means for producing individual voltage signals corresponding to the series of amplitudes stored in each memory;
  - c. adjustable means for operating said read-out means at the same desired reading rate for each memory;
  - d. a corresponding plurality of control means for varying as desired the magnitudes of said individual voltage signals;
  - e. an output terminal for receiving the individual electrical signals to produce a combined output signal having the desired electrical wave shape.
2. Apparatus according to claim 1, in which each memory comprises a voltage source, and a series of resistors connected thereto and adapted to provide individual voltages corresponding to the stored amplitudes, and each read-out means comprises a terminal and individual connections to said resistors, said adjustable means comprising a clock pulse generator connected to a cascade of binary counters corresponding with the number of resistors for successively energising the resistors and producing a continuous series of voltage signals at said terminal.
3. Apparatus according to claim 2, in which each control means comprises a variable amplifier connected to the terminal of the corresponding read-out means of each memory, a selection knob, a variable resistor having a slider interlocked with said knob, an adjustable resistor circuit connected to said slider, and a voltage source for energizing said resistors, a gain control circuit being provided to receive a voltage from said resistors determined by the position of said slider and apply a control voltage to said variable amplifier which thereby produces an individual voltage signal dependent on the operation of the selection knob.
4. Apparatus for synthesizing electrical wave shapes for conversion into musical tones, comprising
  - a. a plurality of wave shape memories in which digital signals are stored corresponding to respective consecutive series of sample amplitudes of a fundamental sinusoidal wave and of selected harmonics thereof;

- b. a corresponding plurality of read-out means coupled to the memories for producing individual digital signals out of storage from the memories;
  - c. adjustable means for operating the respective read-out means at the same desired reading rate for each memory;
  - d. a corresponding plurality of control means for producing respective digital control signals, each digital control signal corresponding to a respective tone color;
  - e. a corresponding plurality of multiplier means respectively coupled to corresponding ones of said memories and said control means for multiplying each read-out digital signal with its corresponding digital control signal to produce respective digital product signals;
  - f. digital adder means for adding said digital product signals from said plurality of multiplier means to produce a digital sum signal; and
  - g. a digital-to-analog converter means for converting said digital sum signal to an analog output signal having the desired electrical wave shape.
5. Apparatus according to claim 4, wherein said read-out means comprises a cascade-connected binary counter, the input of which is connected to a clock pulse generator, the outputs of which are connected in common to the inputs of a plurality of decoders, each of said decoders having a plurality of output lines connected to respective read-out control terminals of one of said memories and providing a read-out signal on one of the output lines corresponding to the count of said binary counters.
6. Apparatus according to claim 4, wherein each of said control means comprises a selection knob, an adjustable resistor having a slider interlocked with said knob, a resistor circuit connected to said slider to pro-

duce an analog control signal, a voltage source for energizing said resistor, and an analog to digital converter for converting the analog control signal to the digital control signal.

7. Apparatus according to claim 4, wherein said control means includes means for selectively producing digital amplitude signals respectively representing the amplitudes of the respective tone colors, a plurality of spectra memories in which digital signals are stored representing relative levels of the fundamental wave and the selected harmonics thereof in said desired electrical wave shape, digital multipliers for multiplying the digital signals from the spectra memories with the digital amplitude signals, and digital adders connected to receive the outputs of said multipliers for producing said digital control signals.

8. Apparatus according to claim 7, wherein said means for producing the digital amplitude signals comprise a plurality of tone-color selection knobs, variable resistors each having a slider which is interlocked with one of said knobs, a source of voltage connected across said variable resistors, and analog-to-digital converters for converting the voltages appearing at the sliders of said variable resistors to said digital amplitude signals.

9. Apparatus according to claim 7 in which at least one spectra memory is of a type in which stored information can be changed by writing new information thereinto and which comprises an external input information medium containing information representing the levels of the fundamental wave and of each selected harmonic thereof, and reading means for reading the information contained in said information medium and applying the read information to said at least one memory.
